UNITED STATES PATENT OFFICE.

WILLIAM BANNEN, OF MILWAUKEE, WISCONSIN, ASSIGNOR OF ONE-HALF TO FRED HICKSTEIN, OF MILWAUKEE, WISCONSIN.

CORRUGATED BASE FOR PAVEMENTS.

Application filed February 23, 1926. Serial No. 90,034.

This invention relates to a corrugated base for pavements for roadways and to the method of making such base.

In making bituminous pavement with a concrete base, it has been the practice heretofore to provide interlocking pockets in the base which engage tongues formed in the pavement. These pockets collect water and are a serious handicap in laying the pavement as it is necessary to wait until the pockets have been dried by evaporation or exposure to the sun. This necessarily causes great delay in the actual production of the pavements, and in addition to this, it frequently happens that these pockets contain moisture when the bituminous top layer is placed in position. This defect causes loosening of the top layer with consequent cracking and disintegration.

20 This invention is designed to overcome the defects discussed above, and objects of such invention are to provide a concrete base for a pavement which is so constructed that no moisture collecting pockets are formed although means are provided for interlocking with the top layer.

Further objects are to provide a novel form of base for a bituminous top layer which is so constructed that there is a slant 30 from the center of the base to opposite sides thereof and in which continuous channels are formed from the crown of the base to the sides so that any water that falls within these channels will immediately drain outwardly, thereby avoiding all of the defects noted above.

Further objects of this invention are to provide a novel method of forming the base, such method providing for the easy and 40 quick positioning of the parts during the formation of the base and insuring the results discussed above.

An embodiment of the invention is shown in the accompanying drawings, in which:

45 Figure 1 is a plan view of a portion of a roadway during construction showing the mat and other portions of the members used in producing this base in position.

Figure 2 is a sectional view on the line 50 2—2 of Figure 1.

Figure 3 is an enlarged sectional view on the line 3—3 of Figure 2.

Figure 4 is an enlarged sectional view on the line 4—4 of Figure 2.

Figure 5 is an enlarged sectional view on 55 the line 5—5 of Figure 2.

Figure 6 is a fragmentary view corresponding to Figure 2 showing a section through the base after the mat and other portions have been removed.

60 In practicing this invention, the concrete base is laid and is crowned and comprises a main portion 1 and curbing portions 2 at opposite sides thereof. These portions are separated in any suitable manner to form 65 longitudinally extending channels 3. While the concrete is still soft, wooden strips 4 are positioned within the channel 3 and a center wooden strip 5 is located in the crown or center portion of the rod. These strips are 70 connected by means of cables 6 which are held in place by means of staples 7 and 8 driven into the strips 4 and 5. It is preferable that the staples 7 be relatively loose so that the cable 6 may be tightened by drawing on their free ends 6'. Thereafter, the staples 7 are tightened as desired. A platform or boarding 9 is laid on the mat thus formed and a roller or other device of the type is passed back and forth over the platform to thus press the cables or members 6 in place as shown in Figure 4 within the soft concrete. This forms a series of pockets 10 (see Figures 4 and 6) which extend continuously from the crown of the pavement to 80 the channels 3 and are unbroken from one end to the other.

85 It is to be distinctly understood that in place of the cables 6, rods or other members of this type may be provided, and it is also to be understood that the channels 10 might not necessarily extend straight across the roadway, but may be made slanting, zigzagging, or in any other shapes providing, however, that the essential idea of this invention 95 is followed to provide a series of continuous channels from the crown of the road to opposite sides thereof.

90 After the members 6 have been forced into the concrete, the boarding 8 and the entire 100 mat is moved to the next portion of the concrete to be treated and the concrete is allowed to harden.

105 It is apparent, therefore, that a series of channels for interlocking engagement with the bituminous top layer have been provided by this method and that these channels are unobstructed from the crown to the outer

end and slant downwardly to the edges of the roadway. These channels, therefore, will not collect water and will not pocket any moisture, instead any moisture that finds its way into these channels will immediately drain to opposite sides of the roadway and into the longitudinal channels 3 which is most clearly brought out in Figure 3. The transverse channels 10 interlock with the bituminous top layer of the pavement and secure all of the desirable results due to this interlocking. However, it is not necessary to wait until a dry sunny day in order to lay the bituminous top layer for it is apparent that the concrete when it has fully set is in condition for the immediate reception of the bituminous top layer irrespective of weather conditions.

It will be seen, therefore, that a material shortening of the time necessary for laying this type of pavement is secured by this invention. Further, it is to be particularly noted that the process may be very expeditiously followed in a simple manner.

It is to be noted further that the apparatus required for the process is extremely simple.

It is to be noted further that a novel form

of base has been provided for insuring draining or drying and which may be very cheaply and quickly produced.

Although the invention has been described in considerable detail, such description is intended as illustrative rather than limiting as the invention may be variously embodied and as the scope of such invention is to be determined as claimed.

I claim:

The method of making a concrete base for an interlocking pavement, said method comprising placing a layer of concrete on the roadway, crowning the concrete, placing a center board and marginal boards in the concrete, stretching flexible members between said boards and securing them thereto, forming a platform over said flexible members and passing a roller thereover to apply a gradual pressure to said platform, and subsequently removing said flexible members and platform and boards.

In testimony that I claim the foregoing I have hereunto set my hand at Milwaukee, in the county of Milwaukee and State of Wisconsin.

WILLIAM BANNEN.
